(57) **CLAIM**

The ornamental design for a display screen, or portion thereof, with a graphical user interface, as shown and described.

DESCRIPTION

The FIGURE is a front view of a display screen, or portion thereof, with a graphical user interface showing the new design.

The outermost dash-dot broken line rectangle illustrates a display screen, or portion thereof, that forms no part of the claimed design. The remaining broken lines illustrate portions of the graphical user interface that form no part of the claimed design.

1 Claim, 1 Drawing Sheet
